SANITATED SHOE TREE CONSTRUCTION

Samuel M. Abrams and Albert Abrams,
Brooklyn, N. Y.

Application January 18, 1946, Serial No. 642,001

2 Claims. (Cl. 12—128)

1

This invention relates to improved sanitized shoe tree constructions, and more particularly is directed to shoe tree constructions when in effective position for efficiently dissipating odors from the interior of shoes after being worn and thereby provide healthier and more comfortable footwear for those persons disposed to have perspiring feet and yet retain the shape of the shoes between wearing periods.

Among the objects of the invention is to generally improve shoe tree constructions of the character described which shall comprise few and simple parts that are readily assembled to form neat and attractive devices or appliances, which shall be readily adapted to conform to shoe shape requirements of a relatively large range of shapes and various sizes, which shall be easy to adjust, which shall be convenient and serviceable to provide a sanitary, hygienic footwear shape retaining device, and which shall be practical and efficient to a high degree and use.

Other objects of the invention will in part be obvious and in part be pointed out.

The invention accordingly consists of features of construction, combination of elements and arrangements of parts which will be exemplified in the constructions hereinafter described and of which the scope of application will be indicated in the following claims.

In the accompanying drawing in which is shown various possible illustrated embodiments of the invention,

Fig. 1 is a front elevational view of the improved sanitized shoe tree constructed to embody the invention partly broken away to expose the interior structure, and showing in dotted lines the installation thereof in a shoe.

Fig. 2 is a bottom plan view of the improved sanitized shoe tree shown in Fig. 1.

Fig. 3 is a cross sectional view taken on lines 3—3 in Fig. 1.

Fig. 4 is a front elevational view of a modified form of sanitized shoe tree constructed to embody the invention partly broken away to expose the interior structure and showing in dotted lines the installation thereof in a shoe.

Fig. 5 is a bottom plan view partly in section, of the improved sanitized shoe tree shown in Fig. 4, and

Figs. 6 and 7 are cross sectional views taken on lines 6—6 and 7—7 respectively, in Fig. 4.

Referring in detail to the drawings, 10 denotes a sanitized shoe-tree constructed to embody the

invention and shown in Fig. 1 in effective position within a shoe of any well understood construction and indicated by dot and dash lines in Figs. 1 and 4 for retaining the shape of the front end thereof between wearing periods and to deodorize or mask odors from the interior of the shoe.

Said shoe tree 10 may comprise a toe bracing structure 11 made of sheet material of metal, plastics or other suitable substances molded or stamped in the well understood manner to provide a hollow light-weight body shaped to conform to the front interior of the shoe and provided with an inturned rim flange 11a to stiffen said hollow structure 11. There also may be provided integral spaced lugs 11b projecting from the rear end of said toe bracing structure 11. Said lugs 11b serve as supports on which end 12a of a U-shaped stretcher 12 is trunnioned by means of pivot member 13 which extends through said lugs 11b and stretcher end 12a. As seen in Figs. 1 and 2, stretcher end 12a may be provided with a cross extended portion 12b to stiffen the interconnecting structures.

The toe bracing structure 11, as seen in Figs. 1 and 3 and as described above, forms a stiff shell with an open bottom side 11c. Said shell structure 11 preferably is formed with through-openings on the top side as for example longitudinally extending spaced slots 11d and grouped perforations 11e. There may also be provided a pair of centrally located, spaced parallelly aligned depressed slit rim edges 11f between slots 11d and located to have the grouped perforations 11e therebetween. Said rim edges 11f serve as a slide-way for outwardly extending flanges 14a for removably retaining a carrier receptacle or compartment drawer 14 positioned in said shell structure 11 with the open side 14b of the drawer 14 facing the perforations 11e as shown in Figs. 1 and 3.

The compartment drawer 14 beside having outwardly extending flanges 14a may be constructed and arranged to hold a suitable neutralizing, counteracting or masking deodorant or absorbent or disinfectant filler F of any well known composition and is perforated or made of mesh sheet material providing through-passages 14c so that the vapors or odors on the interior of shoe have ready access to the deodorant or absorbent filler F which may be volatile. The latter may be a suitable liquid or paste retained on cotton, gauze or the like, or activated granular material but of a size that will not sift through said passages 14c, or

may be made in form of a cake that presents activated surfaces for deodorizing or absorbing, or both.

The practical application of the invention will now be apparent. After constructing and assembling the improved shoe-tree 10 as described above and as shown in Figs. 1, 2 and 3, said shoe-tree 10 may be charged with a suitable deodorant, absorbent, or both, filler F by placing the same in compartment drawer 14 which may be removed from the effective position shown in Figs. 1, 2 and 3 by sliding flanges 14a rearward on slide-way rim edges 11f to give free access to the drawer open side 14b after which it may be reseated into said effective position. The charged shoe-tree 10 can be readily inserted in the shoe with the bight end 12c of the U-shaped stretcher 12 contacting the rear end or counter of the interior side of the shoe thereby firmly retaining the charged shell 11 in effective position. The shell open bottom side 11c, slots 11d and perforations 11e all serve to expose the interior of the front of the shoe to the action of the filler F for counteracting, masking or absorbing odors from said shoe interior.

When the shoe tree 10 is not in use, or when using with shoes constructed with no rear or counter, the stretcher 12 may be swung on pivot member 13 into the position indicated in dotted and dash lines in Figs. 1 and 2. In this latter position the stretcher 12 encircles the drawer 14 and is wholly housed within the shell 11 in compact form.

In Figs. 4 to 7 inclusive, a modified form of shoe-tree construction embodying the invention is shown.

Here the shoe-tree designed generally at 20 has a shell structure 21 similar to the shoe-tree shell 11 above described, except that instead of providing a centrally located compartment drawer 14, there is provided a plurality of drawers 24 spaced apart and utilizing depressed slotted rim edges 21f and a portion of the turned flanges 21a as the slideway for each of said drawers 24.

Integral lugs 21b projecting rearward from the shell structure 21 may be constructed as a telescoping support instead of being pivoted for the U-shaped stretcher 11 of shoe-tree 10. Said telescoping support has pairs of slideway guides 21h for each of the ends 22a of stretcher 22 and may also be provided with suitable length adjustment means, as for example, spaced opening 22d in said stretcher and 22a which cooperate with spring tongues 21d provided in lugs 21b as shown in Figs. 1 and 7. Thus an effective adjusted length of the stretcher 22 can be had as required for various sizes of shoes as is clear from Fig. 1.

The shoe-tree 20 may be used in the same manner as described above for shoe-tree 10. However, a greater capacity of filler F material in drawers 24 is provided, than in drawer 14 and spaced elongated slots 21g, perforation 21e and open bottom 21c provide a greater exposure of the interior of the shoe to the effective action of the filler F in drawers 24 than in the shoe-tree 10. The drawers 24 of shoe-tree 20 may be manipulated at any time for opening and closing same. The stretcher 22 may be collapsed by releasing the tongues 21d from the openings 22d by pressing the stretcher end 22a together and sliding the stretcher 22 into the shell 21 in

the position shown in dot and dash lines in Figs. 4, 5 and 6. In said collapsed position of the stretcher 22 which is then wholly within the shell 21, the drawers 24 remain unobstructed. The drawers 24 may each be made of perforated or mesh sheet material with through-opening 24b like in drawer 14.

It is to be understood that the construction of shoe-trees 10 and 20 may be made to conform 10 with features substituted in each other without departing from the invention.

It is also contemplated to utilize said shoe trees constructions 10 and 20 in moist, damp and hot climates where a suitable effective disinfectant, or anti-fungus or like filler F may be provided to prevent mildew and mold or other deterioration:

It will thus be seen that there is provided 20 sanititated shoe tree constructions in which the several objects of this invention are achieved and which are well adapted to meet the condition of efficient and practical use.

As various possible embodiments might be made in the above invention, and as various changes 25 might be made in the embodiments above set forth, it is understood that all matters herein set forth or shown in the accompanying drawing are to be interpreted as illustrative and not in a limiting sense.

Having thus described our invention we claim 30 as new and desire to claim by Letters Patent:

1. A shoe tree comprising a hollow shoe-shaped toe retaining portion, a collapsible extension movably supported from said toe portion for adjustment in and out of said hollow toe portion, 35 a porous member secured to an interior wall of said hollow shoe shaped portion and so located as to be free from interference with the movement of said collapsible extension when positioned in said toe portion and forming with the toe portion a compartment adapted to receive an odor neutralizing means, said toe portion where it forms the wall of said compartment having openings 40 therein and having passages therein communicating with the interior thereof at points spaced from said openings, and means permitting movement of one of the portions forming a wall of said compartment so as to permit the insertion and removal of odor neutralizing means.

50 2. A shoe tree as defined in claim 1 in which said means permitting movement of one of the portions forming a wall of said compartment includes inwardly pressed portions of said toe retaining portion.

55 SAMUEL M. ABRAMS.
